Primary Examiner—Alan P. Douglas*Assistant Examiner*—Jennifer Rivard*Attorney, Agent, or Firm*—Pennie & Edmonds LLP[57] **CLAIM**

The ornamental design for a power strip, as shown and described.

DESCRIPTION

FIG. 1 is a top view of a power strip having a cable manager along right and left sides thereof according to the present invention;

FIG. 2 is a front elevational view thereof;

FIG. 3 is a left side elevational view, the right side elevational view being a mirror image thereof;

FIG. 4 is a rear elevational view thereof;

FIG. 5 is a bottom view thereof;

FIG. 6 is a top view of a second embodiment of a power strip having a cable manager along right and left sides thereof according to the present invention, with the outlets, power button, indicator lights, and reset button being shown in broken lines and thus not constituting a part of the claimed design;

FIG. 7 is a front elevational view of the power strip of FIG. 6;

FIG. 8 is a left side elevational view of the power strip of FIG. 6, the right side elevational view being a mirror image thereof;

FIG. 9 is a rear elevational view of the power strip of FIG. 6; and,

FIG. 10 is a bottom view of the power strip of FIG. 6.
